UNITED STATES PATENT OFFICE.

CHARLES FABIAN, OF AUCKLAND, NEW ZEALAND, ASSIGNOR TO ROSS GOULD LIMITED,
OF AUCKLAND, NEW ZEALAND.

FLUSHING SYSTEM.

Application filed August 10, 1927, Serial No. 212,051, and in New Zealand August 24, 1926.

This invention has been devised with the object of providing improved flushing means that ensure a rapid and silent flush, and also a complete flush of the cistern's contents before being shut off.

These means are designed to be controlled by a flushing valve which seats itself over the discharge orifice to seal it and is maintained in such position by the air suction when the cistern fills. Such seal is then broken through lifting the valve slightly by special operating means provided, so that the valve rises in the cistern and allows the flush to take place, and at the close of the flush the valve is drawn back on to its seat. The operating means are of special design adapted to lift and free the flushing valve, and then to automatically return to the operative position on the valve falling and the cistern filling again.

The invention is illustrated in the accompanying drawings and will be hereinafter fully described in relation to such drawings, in which:—

25 Figure 1 is a sectional side elevation of a cistern with the fittings in position therein. Figure 2 is a sectional end elevation of the cistern showing the fittings therein, but with certain parts removed for the purpose of clearness of illustration.

Figure 3 is a detail view on an enlarged scale, of the flushing valve and its seat (which are shown in section) and of the valve lifting lever, shown in elevation.

35 In this invention, the cistern A is provided with the tubular discharge fitting B opening through its bottom, and to the lower end of which the down pipe C is connected. This fitting is made with a valve seat b around its upper end and a flushing valve D is provided to fit over such seat to close the discharge outlet. This valve D on its underside has a rubber ring d secured thereon, which ring is adapted to seat itself within the valve seat b and make an effectual water and air tight joint therewith.

The flushing valve D is fixed to a vertical hollow rod E passing through it, and the lower end of this rod is guided within a bearing F arranged in the fitting B while its upper end passes through the top of a guide frame G that is fixed to or made in one with the fitting B. This rod, by being thus mounted, therefore keeps the flushing valve in position over the outlet of the fit-

ting B and permits of it rising and falling to open and close the outlet. The upward movement of the flushing valve is controlled by a suitable stop, as for instance the stop e fixed on the bottom end of the rod E and 60 adapted to engage the bearing F when the rod lifts far enough to give the required full discharge clearance between the float valve and its seat b.

The upper end of the rod E is provided 65 with an enlarged head or collar H fixed thereon.

A lever arm J is provided and pivoted in an extension G' from the top of the frame G. The inner end of this lever extends horizontally and is adapted to fit beneath the collar H, while its outer end is curved downward in the cistern and has a float K secured thereto. This float K, when the cistern is charged with water, is designed 70 by its buoyancy to keep the lever in such position as to cause its inner end to extend horizontally, and to return it to such position should the inner end be lifted. Such 75 inner end is constructed, as shown in Figure 3, with its extremity formed as a pawl J' that is pivoted to the main part in such a manner that it may turn freely in an upward direction but is kept uniform with the main portion by reason of its weight and 80 kept from turning downward.

This lever pawl end J' engages beneath the collar H of the valve rod E when such rod is in its lowered position and the valve D is upon its seat, and on an upward movement 85 being given to the lever, is designed to lift the rod slightly and then pass up beyond such collar H.

For lifting this lever J in such manner and then freeing it so that it may drop again, 90 an actuating lever M is provided and pivoted to extend transversely across the top of one edge of the cistern, as by being mounted on an upward extension G² of the frame G. The outer end of this operating lever has the 100 ordinary pull chain attached to it. Its inner end has a bar N fixed to it to extend downward and such bar is formed with a slot n extending longitudinally and through which slot the inner end of the lever J passes loosely. This slot is made of such a length as to provide that when the inner end of the lever M is raised, the lower end of the slot 105 will engage the lever J and lift it in the manner required, and then when the pull on the 110

outer end of the lever M is released, the inner end will be free to fall by its own weight, the slot passing idly over the lever J without moving it.

- 5 In the operation of the invention, the cistern being empty, the flushing valve will seat itself on the outlet and make an air-tight joint therewith and will maintain its seat as the cistern fills by reason of the air suction beneath it. When a flush is to be effected, the lever M is operated and this, by lifting the lever J, causes its pawl end J' to engage beneath the collar H of the valve rod E and to raise such rod sufficiently to 10 break the seal of the flushing valve D upon its seat b before passing to above the rod end. The seal then being broken, the valve D will rise in the water to the limit provided for, thereby opening the discharge to its full. As 15 the discharge finishes, the flushing valve is drawn down with the rush of the water so that it re-seats itself upon the seat b to seal the opening and allow the cistern to refill. Any air suck, and the attendant noise as 20 the flush finishes, are obviated by having the rod E hollow throughout its length.

Meanwhile the lever J, having been raised, is retained in the raised position by the dropping of its float end with the lowering of 25 the water level, as the discharge commences. It remains in such position until the cistern is again about full and has its inner end lowered with the rise in the water level until it reaches its normal position, the pawl end J' passing freely over the collar H of the valve rod E which has previously 30 dropped, and positioning itself again beneath such collar ready for the next flushing operation. The slot in the connecting bar 35 N allows the pull on the lever M being released as soon as the flush commences fully,

the float K being properly adjusted in its level to fall immediately the water level begins to drop.

The water supply to the cistern is controlled in the usual way through a float governed valve O of well known type, and combined with this valve is a silencer device P.

I claim:—

1. In a flushing system, the combination with a cistern, and a flush outlet in the bottom of such cistern having a valve seat opening, of a flushing valve constructed with a bottom adapted to engage and seal such opening, a vertically extending rod fixed to said valve and having an enlarged head on its upper end, a lever pivoted in the upper part of the cistern and having at its inner end a hinged pawl adapted to engage beneath such head and to lift the rod when such lever end is raised, a float upon the outer end of such lever, an operating lever mounted on the cistern, and a connection between the operating lever and the inner end of the lifting lever.

2. In a flushing system according to claim 1, a connection between the said operating lever and the lifting lever, such connection consisting of a bar depending from one end of the operating lever and having a slot extending longitudinally therein through which the said lifting lever passes loosely.

3. In a flushing system according to claim 1, a guide frame for the flushing valve rod and through which it may move longitudinally, constructed with extensions for pivoting the respective lifting lever and the operating lever thereon.

In testimony whereof, I affix my signature.

CHARLES FABIAN.
